BASKET FOR FRUIT OR THE LIKE

Jack V. Barnes, 29911 Katella Ave., Laguna Beach, Calif.,
and Thomas C. Hunter, 6813 Atlantic Blvd., Long Beach, Calif.

Filed Mar. 13, 1963, Ser. No. 73,961

Term of patent 3½ years

(Cl. D58—4)

FIG. 1

We claim:

The ornamental design for a basket for fruit or the like, substantially as shown.
